D12-203. OR D 13,419 EX

Design No. 13,419, dated November 14, 1882.

UNITED STATES PATENT OFFICE.

JOHN L. POPE, OF CLEVELAND, OHIO.

DESIGN FOR A CARRIAGE-STEP.

SPECIFICATION forming part of Design No. 13,419, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Carriage-Steps, of which the following is a specification, reference being had to the accompanying photographic illustration, forming part thereof.

My invention relates to a new design for carriage-steps; and it consists in ornamenting the upper surface thereof with trifurcated ribs or raised pieces, as will be hereinafter more particularly described.

In the photographic view which accompanies this specification and forms a part thereof, the plate therein shown has surface ornamentation composed of numerous trifurcated raised bars or ribs, a few of which I have marked with the letter *a*. I have so arranged these forked ribs *a* that they form a series of contiguous unfinished star-like figures, as may be quite readily

traced out by the eye, the middle of each of which star-like figures is indicated by the circular portion of the plate which I have marked *b b b b*, &c. Surrounding the trifurcated figures *a a* is a raised border running obliquely at each corner of the step.

What I claim as my invention, and desire to secure by Letters Patent, is—

1. A design for a carriage-step, consisting of surface ornamentation composed of trifurcated ribs, substantially as shown.

2. A design for a carriage-step, consisting of surface ornamentation composed of forked ribs laid out in star-like figures, with or without the border, substantially as shown.

In testimony whereof I have hereunto set my hand this 31st day of May, 1882.

JOHN L. POPE.

In presence of—

A. A. POPE,

C. M. COPP.
